UNITED STATES PATENT OFFICE.

WILLIAM R. HOLLINGSHEAD, OF ALLEN TOWN, PENNSYLVANIA.

RECEPTACLE-HOLDING DEVICE FOR BOXES.

1,201,047.

Specification of Letters Patent. Patented Oct. 10, 1916.

Application filed April 16, 1915. Serial No. 21,762.

To all whom it may concern:

Be it known that I, WILLIAM R. HOLLINGSHEAD, a subject of the King of Great Britain, having resided in the United States 5 one year last past and having declared my intention of becoming a citizen thereof, residing at Allentown, in the county of Lehigh, State of Pennsylvania, have invented a new and useful Receptacle-Holding Device for Boxes, of which the following is a 10 specification.

My invention consists in providing a box or other package of similar nature or the like with a retainer for tubes, vials, bottles, 15 or other similar receptacles packed therein, so as to control the same in a firm, non-shiftable, safe and non-injurious manner.

It consists also of a device adapted to be interposed in the box over said retainer between 20 the latter and the lid of the box to prevent rising of the receptacles and so hold them most firm as packed in the box.

The invention is satisfactorily illustrated in the accompanying drawing, but the important instrumentalities thereof may be varied, as long as they are included in the 25 scope of the claims.

Figure 1 represents a perspective view partly cut-away of a receptacle-holding device for a box embodying my invention. Fig. 2 represents a transverse section on line $x-x$ Fig. 1. Fig. 3 represents a perspective view of a holding device detached in condition preparative to connection with 35 a box. Fig. 4 represents a bottom plan view of a portion of the box on a reduced scale. Fig. 5 represents a section of a modification.

Similar numerals of reference indicate corresponding parts in the figures.

40 Referring to the drawings:—1 designates a box which excepting the features of my invention applied thereto is of usual construction.

2 designates a holding device or rack for 45 tubes, vials, bottles or other similar receptacles placed or packed in the box, the same in the present case being of the form of collapsible tubes 3, having necks 4 on which are closing caps 5, as well known.

50 The device 2 comprises a rack composed of a piece of material, preferably sheet metal, which is bent on itself in longitudinal direction, forming the plurality of side walls 6, and the piece 7 which joins the bottoms of the inner members of said walls and separates the latter forming between

them the space or passage 8, said piece 7 also forming a broad base by which the device is supported flat on the bottom of the box and so sustained and steadied in the box.

The walls 6 which occupy upright positions in the box have therein the vertically-extending recesses 9 which extend through the top bend of each pair of walls 6 into said walls to near the lower ends thereof. In the primary condition of the device the ends of the walls 6 have projecting therefrom the horizontally-extending lips 10, and the under edges of said wall have projecting therefrom the downwardly extending lips 11, it being seen that when the device 2 is placed on the bottom of the box 1 and rested thereon, then the lips 10 are passed outwardly through slits in the sides of the box 75 and bent over the exterior of said sides thus clenching said lips and thereby firmly connecting the device with said ends, see Fig. 1. The lips 11 are passed downwardly through slits in the bottom of the box and 80 bent over the exterior of said bottom thus firmly clenching said lips and thereby connecting the device with said bottom, see Fig. 4.

The tubes are inserted in the box with 85 their necks and caps occupying the recesses 9 and occupying the bottoms of the latter as seats therefor, so as to sustain the neck end of the tubes and limit the descent thereof. At the same time, the caps of the tubes 90 occupy the passage 8 and as there is a plurality of rows of tubes, the caps of opposite tubes face each other in said passage, the walls 6 preventing said caps from contacting and being crushed one by the other. At 95 the same time, the tubes are controlled by said walls, whereby they cannot shift from or toward each other and so are retained solidly in the box without liability to be battered or deteriorated in appearance.

In order to still further control the tubes in the box I employ the binder 12 which consists of a piece of suitable pliable material longitudinally channeled so as to be fitted over and straddle the cap or neck-portions 105 of adjacent pairs of tubes and have its sides or legs 13 bear downwardly upon said portions and its top 14 is engaged by the lid or cover 15 of the box and held in place by the same, thus pressing the neck portions 110 of the tubes gently but firmly on their seats at the base of the recesses 9, whereby ris-

ing of the tubes therefrom is prevented, the tubes thus being clamped in horizontal and vertical directions in the box, the effect of which in preserving the fine appearance of the tubes when the box arrives at its destination and the box is opened is evident.

In Fig. 5 I show an end view of a retainer formed of wood of one or more pieces, the same having recesses in the side walls thereof, similar to those shown in the other figures, said walls being adapted to be secured to the sides and bottom of the box by nails, tacks, glue or other means.

Having thus described my invention what I claim as new and desire to secure by Letters Patent, is:—

1. A rack insertible in a box, said rack having a base and being formed of a plurality of double walls bent on themselves forming a quadruplication of walls integral with the base, the passage between the innermost adjacent walls being adapted to receive the closing devices of opposite receptacles end to end, said plurality of walls having therein alined recesses opening in the top bends of said walls.
2. A rack insertible in a box, said rack having a base and being formed of a plurality of double walls bent on themselves forming a quadruplication of walls integral with the base, the passage between the inner-

most adjacent walls being adapted to receive the closing devices of opposite receptacles end to end, said plurality of walls having therein alined recesses opening in the top bends of said walls, and lips on the walls extending therefrom to enter openings in the sides of the box and to be secured thereto.

3. In a package having a device therein for retaining a receptacle adapted to occupy the box, a binding member formed of a top wall and legs depending therefrom adapted to be placed over said device and have said legs straddle a portion of said receptacle and have said top wall engaged by and be held down by the lid of the package.

4. In a package having a device therein for retaining a receptacle adapted to occupy the box, a binding member adapted to be placed over said device and straddle a portion of said receptacle and be engaged by and held down by the lid of the package, said member being composed of a top wall, and side walls depending therefrom forming a longitudinally extending channel in the member between said legs.

WILLIAM R. HOLLINGSHEAD.
